UNITED STATES PATENT OFFICE.

WILLIAM C. PERRY, OF CHARLESTOWN, RHODE ISLAND.

CAR-SPRING.

SPECIFICATION forming part of Letters Patent No. 364,286, dated June 7, 1887.

Application filed October 4, 1886. Serial No. 215,329. (No model.)

To all whom it may concern:

Be it known that I, WILLIAM C. PERRY, of Charlestown, in the county of Washington and State of Rhode Island, have invented certain new and useful Improvements in Car-Springs, of which the following is a specification, reference being had to the accompanying drawings, making part hereof.

This invention is an improvement in car springs and trucks, the object being to secure great elasticity with simplicity and cheapness of construction. In some of its features my present improvement resembles another invention in vehicle-springs, for which my application for patent is filed simultaneously herewith.

The features peculiar to this invention are a series of elliptic or equivalent springs on the truck supporting a fulerum-bar, in combination with a series of crossed levers pivoted centrally or otherwise on said bar and connected at their ends to the truck-frame and car-frame by yielding connections.

My invention consists in the combinations of devices hereinafter described, and especially referred to in the appended claims.

In the accompanying drawings, Figure 1 is a plan of part of a car-truck provided with my improved springs. Fig. 2 is a section thereof on the line $x-x$, Fig. 1. Fig. 3 is an end elevation of a similar construction.

A represents the frame of the truck, which will be of any suitable construction, and provided with wheels, axles, bearing-boxes, &c., in the usual way. These parts are not herein shown, since my invention does not involve any peculiarities of their construction.

B B are springs (shown as of elliptic form) mounted in a series of three or more on the frame of the truck, and connected transversely by a stout fulerum-bar, C, which rests on or is supported by said springs. This bar

serves as a fulerum for the crossed and pivoted levers D, which at their ends are united to the truck-frame and the car-body by suitable yielding connections, so that when the springs are compressed and the levers depressed by the weight in the car-body the ends of the levers may move outwardly to a proportionate extent.

With the arrangement shown in Figs. 1 and 2, the fulerum-bar rests on and is secured to a clip, E, surrounding the leaves of the spring. The lower ends of the lever D have a longitudinal movement on elongated staples F, while their upper ends are shown slotted to receive pins, thus permitting suitable yielding at each end.

In Fig. 3 swinging links G connect the levers, respectively, to the frame A and the base H of the car-body, the clip E serving to suspend the bar C within the springs B—that is, below the upper member of the several springs. These two forms are regarded as equivalents, and may be substituted one for the other.

Having thus described my improvements in car-springs, I claim as my invention—

1. The truck-frame A, supporting the series of springs B, in combination with the bar C, and the pivoted levers D, fulerumed on said bar and joined to the frame and car-body by suitable yielding connections, substantially as set forth.

2. The combination of a series of elliptic springs with a series of crossed levers fulerumed on a bar supported by said springs and connected thereto by clips E, embracing the leaves of the springs, substantially as set forth.

WILLIAM C. PERRY.
